UNITED STATES PATENT OFFICE

MATTHEW LEE HEALD, OF PORTLAND, MAINE, ASSIGNOR TO AMERICAN CAN COMPANY, OF NEW YORK, N. Y., A CORPORATION OF NEW JERSEY

SCROLL SHEAR DEVICE

Application filed April 26, 1928. Serial No. 272,897.

The present invention relates to shear presses provided to cut a sheet of metal as tin plate and the like into transverse strips of predetermined form and dimensions, and it has more particular reference to presses of this sort wherein the edges are given a configuration of special form as for example, the staggered or undulating scroll formation not infrequently provided where the cut strips are intended to be fed into a punch press for the production of can ends for the ordinary tin cans of commerce.

It will, of course, be readily appreciated that in the production of can ends and other articles of nonrectangular form care is taken to provide the strips of such shape and dimensions as to produce minimum waste. This requires first a careful and economical layout of the sheet itself, and second, the accurate operation of the shear press in accordance with the layout. In the manufacture of can ends, the strip is given the undulating or scroll edge well known in the art, the enlarged parts of one strip mating with the large parts of the adjacent strips. Differently stated, in the layout the can ends to be cut from a predetermined strip are alternately laid out with respect to those to be cut from the strips next adjacent. A sheet of tin plate customarily provides strips to be fed to the forming or punch press in number varying with the size of the can ends to be produced, six or seven of such strips being usual.

The sheet is automatically fed to the shearing die in position to have the forward edge trimmed to scroll form. At the next advance of the feeding mechanism, the sheet is arranged so that the dies cut off two strips at one stroke, one said strip lying beyond the dies and one within their cutting edges. This operation is repeated until at the last cut for the sheet three strips are produced, one in front of the dies, one between them, and one in back of them, the last strip having an edge that is straight since it does not come under the die influence.

My invention has for its object broadly the improvement in the gauging and registering devices for insuring that the successive pres-

entations of the sheet parts to the dies will be accurate and this without interfering with the operation of the shearing mechanism or requiring redesign thereof or of feeding mechanism heretofore employed.

One principal object of the invention is to make certain that the sheet is first received at the shearing station and there arranged for shearing in accurate position; another principal object is the re-registration of the sheet after each cut to insure against disarrangement as a result of the shearing action and the subsequent advance of the sheet for the next cut; and still another principal object of the invention is to insure against improper movement of the sheet during the cutting operation and as a result of it.

Another important object of the invention is the provision of mechanism which will accomplish the foregoing and other desirable results in positive fashion and through the movement of proper parts and devices and this without the provision of delicate or complicated construction or the provision of parts likely to require frequent repair, replacement or adjustment.

Numerous other objects and advantages will be apparent from the following description, which, taken in connection with the accompanying drawings, discloses a preferred embodiment thereof.

Referring to the drawings, Figure 1 is a side elevation of a shear press embodying my present invention;

Fig. 2 is a top plan view of the same, the upper portion of the guide frame for the active punch being removed;

Fig. 3 is a partial section taken substantially on the line 3-3 of Figure 2;

Fig. 4 is a transverse partial sectional view, taken substantially on the line 4-4 of Figure 2;

Fig. 5 is a fragmentary sectional detail, taken substantially on the line 5-5 of Figure 2;

Figs. 6, 7 and 8 are sections taken upon the line 3-3 of Figure 2, and showing the arrangement of the parts at different stages of the shearing of the sheet;

Fig. 9 is a plan detail showing one of the

gauging devices in operative relation with respect to a sheet edge; and

Fig. 10 is an enlarged detail of a portion of the same and showing its action.

5 For the purpose of illustrating my present invention, I have shown on the drawings a scroll shear press of well-known construction. It comprises the usual base 21, side supports 22, auxiliary support 23, bed plate 24, table 10 extension or bed 25 and the shearing is accomplished by the usual die organization comprising fixed dies 26, reciprocating die 27 and power means for reciprocating the die 27 to accomplish this shearing. This power 15 means comprises a main or power shaft 28, which carries an eccentric 29. This eccentric in turn through eccentric strap 31, connecting pitman or arm 32, and vertical slide 33 causes the die 27 to move to and within the 20 die 26 at each shearing stroke of the press.

Referring to Figure 2, the sheets to be sheared are indicated at 36 and these sheets are delivered successively onto the left hand end of the bed where they are caused to advance by continuously moving feed chains 37, which chains are arranged over sprockets at the ends of their travel, the sprockets at one end of said travel being secured upon a shaft 38, said shaft carrying a drive sprocket 39. 25 A sprocket chain 41 is arranged over the sprocket 39 and also over a sprocket 42 upon an auxiliary shaft 43, this shaft having gear connection at 44 to main power shaft 28.

30 The feed chains 37 perform a preliminary 35 operation, delivering the sheets to the main feed mechanism which will be now described and which advances the sheets between the dies intermittently, an advance being accomplished between the die reciprocations and 40 in timed relation with the shearing organization.

The main feed mechanism comprises a plurality of slides 45 mounted to reciprocate in grooves 46 extending lengthwise of the bed 45 and to adjacent the shearing organization. These slides 45 are provided with upwardly-spring-pressed dogs 47 (Fig. 6), these dogs being arranged to move in and out of recesses 48 in the slide to engage behind the sheet to 50 advance it the desired amount at each reciprocation of the slide. This feeding action in presses of this type is well-known and particular description of it is thought unnecessary. It may be said however that the desired reciprocation is imparted to the slide by a link and lever assembly indicated generally at 49 (Fig. 1) and extending from a pivotal connection at 51 with a slide to a crank pin 52 mounted for eccentric rotation about 55 the shaft 28.

60 It will be readily understood that it is important that each sheet as it arrives at the shearing station be accurately registered and gauged transversely of its path of travel. A 65 fixed gauge or guide 53 is arranged near the

feed end of the bed 25, this guide or gauge being preferably mounted for lateral adjustment. Each sheet as it is received is pressed toward the gauge 53 by a pressure roller 54 (Fig. 2) mounted upon an arm 55 70 and pressed toward the sheet by a spring 56, a stop 57 being provided to hold the roller in sheet receiving position. The arm 55 is carried by an overhead framework in a bracket 58. This framework comprises cross-bars 59 and 61 mounted above the sheet travel and extending across the bed. It comprises also connecting bars 62 secured at their ends to the bars 59 and 61.

75 It will be readily appreciated that the feed 80 chains 37 by reason of their continuous movement deliver each sheet or may deliver each sheet in untimed relation with the reciprocating slide feed member, and throughout the feeding to the shearing organization it is desirable that the feeding movement of the parts be prevented from advancing the sheet more than the travel desired. This is accomplished in the present instance by upper pressure rolls 63 and lower power-driven 85 rolls 64 (Fig. 6). The rolls 63 are mounted upon arms 60 fast to a rock shaft 65 having suitable bearing at 66 above the sheet travel. The shaft 65 is provided at one end with an arm 67 having a cam roller 68 at its free end. 90 This cam roller engages a cam 69 upon a short shaft 71 which shaft is provided with a sprocket 72 over which the sprocket chain 41 already mentioned is trained. The lower rolls 64 are fixed upon a shaft 73 which shaft carries a sprocket 74 driven by a chain 75 from a sprocket 76 on shaft 28. Viewing Figure 1, it will be noted that rotation of the rolls 64 is continuous and in a counterclockwise direction. Portions of the rolls engaging the under surface of the sheet move, therefore, in a direction to carry the sheet away from the shearing organization. The cam 69 normally holds the rolls 63 out of action and is provided with recesses 77 into 100 which the cam roll 68 may drop to bring the rolls 63 into contact with the sheet and press this sheet against the rolls 64 for the restraining or return influence. When the rolls 63 are elevated the rotating movement of the 105 rolls 64 is without effect upon the sheet.

110 When a sheet is first delivered by the chains 37 the rolls 63 and 64 cooperate to accurately register it against spring-pressed detents 78 mounted in housings 79 on the bars 62, these 115 detents extending down behind the rear edge after this edge has passed them.

120 The sheet thus positioned and prior to the first cutting operation is now given a final lateral gauging. A movable gauge plate 81 (Figs. 2, 4 and 5) is mounted in vertical position upon the end of a rod or bar 82 having bearing in a bracket 83 through which shaft 71 extends. A spring 84 embracing the rod 82 and mounted between the bearing 83 and a 125

collar 85 on the rod normally holds the plate 81 in retracted position. The end of the rod 82 is arranged for engagement by a cam 86 fixed upon shaft 71 and moves the gauge plate 81 laterally of the apparatus to engage the presented sheet edge to move the sheet across its path of travel to the desired final position. The fixed gauge 53 earlier described arranges the sheet somewhat out of the registration 10 and nearer to the side of the machine provided with the gauge 81 than is finally desired. The sheet thus positioned and gauged is arranged for the initial cut. Its forward edge extends between the die members and is 15 trimmed in the first die reciprocation as shown in Fig. 6 to the edge scroll form indicated at 91 in Fig. 2. During this cut the rear edge of the sheet rests against the spring-pressed detents 78. During the idle 20 movement of the press shear or die parts, the feed slides 45 advance the sheet between the dies and into position to have two strips cut at the next reciprocation. This position is shown in Fig. 7, a strip part lying beyond the 25 dies and a strip part between them. Just prior to this second reciprocation of the die, the sheet is again engaged both transversely and lengthwise of its travel by mechanism that will now be described. Two locks 92 30 having an edge shape adapting them to mate with the scroll edge formed in the sheet are mounted in position to engage the scroll edge, and by the mating bring the sheet to proper lateral registration. This action is perhaps best understood upon comparing Figs. 9 and 35 10. The blocks 92 are secured to a cross-bar 93 and upper and lower blades 94 and 95 are arranged to direct the edge of the sheet to the plane of the block and to prevent the sheet 40 from moving out of vertical registration during the shearing action.

The sheet is gauged lengthwise of its travel by a gauge bar 96 mounted for reciprocation in the overhead framework composed of bars 59, 61 and 62. Two rails 97 are mounted upon the under side of bars 59 and 61 and cross members 98 rest upon these rails for sliding movement. The bar 96 is secured to the cross members 98 at 99. A lug 101 extends up from the gauge member 96 and receives a bolt 102 which is embraced by a spring 103 bearing against the lug and the collar 104 on the rod. The rod is connected to a lever 105 pivoted at 106 upon its bar 107 connecting bars 59 and 61. This lever carries a cam roller 108 adapted to engage a cam 109 upon shaft 71. The gauge bar 96 is provided with a number of downwardly extending spring-pressed dogs 111, which dogs are so positioned that each reciprocating movement of the feed slides advances the rear edge of the sheet into position for engagement. As soon as the feed slides start back upon the idle stroke, the cam 109 moves the lever in a clockwise direction, viewing Fig.

2, and yieldingly presses the sheet against the blocks 92 to complete the registration. In the present instance, the blocks engage the forward edge of the sheet at two points and a single gauge member 96 is provided, thus 70 insuring a three point registration. A spring 112 connecting bar 96 with cross member 98 holds the cam roller 108 against the cam and renders the action positive.

After the sheet has been thus positioned 75 and gauged, the active die descends to sever the two strips as already described. As soon as the shearing is accomplished, the lower blade 95 is retracted and the strip sheared may fall away for disposition as will be later 80 described. A rock shaft 114 is mounted in brackets 115 above the bed and beyond the shearing organization. Two arms 117 are fast upon this rock shaft and depend to adjacent the lower blades 95 to which they have 85 loose hook engagement at 118. The shaft 114 carries an arm 119 which is provided with a cam roller 121 adapted to engage a cam 122 upon a stub shaft 123 mounted in a bracket 115. A third arm 124 extends from the 90 shaft for engagement by a spring 125 arranged to cause the cam rolls 121 to follow the cam rolls 122. The shaft 123 is continuously rotated by a chain drive which includes a sprocket 126 on shaft 123, a sprocket chain 95 127 extending over sprocket 126 and also about sprocket 128 upon a shaft 129 which is continuously rotated by a sprocket chain 131 from shaft 38. Shaft 129 is mounted beneath the bed 24 for a purpose to be later set 100 forth.

The apparatus shown on the drawings is arranged to make three strip producing cuts and at the last cut three strips are produced as may be observed in Fig. 8, one strip being 105 provided in advance of the dies, one directly through the lower dies, and one behind them. It will be apparent that by adjusting the apparatus greater or less number of strips may be cut from the sheet. In order to insure that 110 the strips after cutting be freed of the die organization and to insure also that the sheet be pressed against the lower dies during the shearing operation, I have provided spring-pressed plungers 132 upon the moving die 115 and arranged in brackets 133 for engagement with the sheet before and after the shearing. Springs 134 are positioned between the brackets and collars 135 fast on the plunger 132.

As the strips are cut they fall into receiving magazines, those being cut in advance of the die sliding down into a magazine formed by angle members 141 and 142. Those being cut between the fixed dies fall upon a guide shelf 125 143 and into an intermediate magazine formed by angle members 144 and 145. The strips cut behind the die are received upon a guiding plate 146 and directed down into a magazine formed by angle members 147 and 130

148. The waste formed in trimming the forward edge of the sheet falls through between the fixed dies and is received upon a guide plate 150 down which it slides and by which it is directed out of the apparatus. In order that none of this waste may be received in the intermediate magazine, the plate 143 is pivotally supported upon a rock shaft 151, which rock shaft carries an arm 152 having a cam 10 roller 153 for engagement with a cam 154 upon shaft 129 already mentioned, this cam lifting the guide plate 143 up and out of the way of the waste indicated at 155 in Fig. 6 when the forward edge of a strip is to be cut.

155. There is, thus, provided an apparatus that receives the sheet 36 on the upper surface of the table 25, the sheet being moved forward by feed chains 37 and positioned laterally of the table by the guide 53 cooperating with the roller 54. The sheet, thus, initially located and advanced over the table is brought into the second feed mechanism comprising the slides 45 which further advance it in a step-by-step movement. The sheet 25 prior to each advance movement of the slides 45 is accurately positioned in their feed dogs 47 by rollers 63 (intermittently operated by connection with the cam 69) cooperating with the power driven rollers 64. Cam 69 makes 30 one complete revolution for the entire operation upon a single sheet and inasmuch as there are four cutting operations on a single sheet, this cam is provided with four recesses 77. In the first position of rest following 35 the first forward feeding action of the slides 45, the sheet is gauged laterally by shifting of the gauge plate 81 operating by connection with the cam 86. Cam 86, like cam 69, makes one complete revolution for all of the operations on the sheet. This cam has only one 40 projection (Fig. 4) and plate 81 is, therefore, only shifted for the first or initial trim operation on the front edge of the sheet. Sheet 36 is next advanced for the second cutting 45 operation, its front edge being now provided with a scroll or undulating edge. The sheet is brought into accurate gauge position just prior to the cutting operation by shifting of the gauge bar 96 engaging the rear edge of 50 the sheet and moving the front scrolled edge into accurate alignment longitudinally and laterally by centering the scroll edge against the gauge blocks 92. Bar 96 is controlled by cam 86 which is provided with three projections (Fig. 5) each projection shifting the bar forward for a gauging operation. These 55 projections are spaced around the cam at 90° intervals, the blank or intervening space passing 60 the actuating mechanism of the gauge bar 96 when the sheet is initially brought into the position for trim at which time no front edge gauging takes place. There now follows three cutting operations, the gauging of 65 the sheet by the bar 96 and the blocks 92 tak-

ing place just prior to each of the three cutting operations.

It is thought that this invention and many of its attendant advantages will be understood from the foregoing description, and it is apparent that various changes may be made in the form, construction and arrangement of the parts without departing from the spirit and scope of the invention or sacrificing all of its material advantages, the form hereinbefore described being merely a preferred embodiment thereof.

I claim:

1. In a shear press adapted to cut a sheet of metal into transverse strips, the combination of a bed across which the sheets of metal are adapted to be successively fed, a shearing organization associated with said bed, a feeding mechanism for advancing said sheets across said bed and operating in timed relation with said shearing organizations, a movable gauging device arranged at a side of the path of travel of the sheets to the shearing organization, cam actuated means acting in timed relation with said feeding device and said shearing mechanism and connected with the feeding mechanism whereby the latter presses said movable device against the side edge of the sheet for gauging said sheets laterally and as incident to the feeding of them to the shearing organization.

2. In a shear press adapted to cut a sheet of metal into transverse strips, the combination of a bed across which the sheets of metal are adapted to be successively fed, a shearing organization associated with said bed, a feeding mechanism for advancing said sheets across said bed and operating in timed relation with said shearing organization, power actuated means acting in timed relation with said feeding device and said shearing mechanism whereby the power of the press acts to press and gauge said sheets laterally and as an incident to the feeding of them to the shearing organization.

3. In a shear press adapted to cut a sheet of metal into transverse strips, the combination of a bed across which the sheets of metal are adapted to be successively fed, a shearing organization associated with said bed, a feeding mechanism for advancing said sheets across said bed and operating in timed relation with said shearing organization, reciprocating means connected with and acting in timed relation with said feeding device and said shearing mechanism whereby the power of the press acts to press and gauge said sheets laterally and as an incident to the feeding of them to the shearing organization.

4. In a shear press adapted to cut a sheet of metal into transverse strips, the combination of a bed across which the sheets of metal are adapted to be successively fed, a shearing organization associated with said bed, a feeding mechanism for advancing said sheets

across said bed and operating in timed relation with said shearing organization, a movable gauging device arranged above the sheet travel and adjacent said shearing organization for moving said sheet into final and accurate shearing position, a fixed gauging device mounted in the path of travel of the sheet and cooperating with said movable device, and a cam connected with the press mechanism and operating in timed relation with said shearing organization for actuating said movable device against the sheet.

5. In a shear press adapted to cut a sheet of metal into transverse strips, the combination of a bed across which the sheets of metal are adapted to be successively fed, a shearing organization associated with said bed, a feeding mechanism for advancing said sheets across said bed and operating in timed relation with said shearing organization, and a fixed gauge device arranged beyond said shearing organization for engaging the presented edge of a sheet and formed to register said sheet accurately both transversely and lengthwise of the sheet.

6. In a shear press adapted to cut a sheet of metal into transverse strips, the combination of a bed across which the sheets of metal are adapted to be successively fed, a shearing organization associated with said bed, a feeding mechanism for advancing said sheets across said bed and operating in timed relation with said shearing organization, a movable device and a fixed gauge device arranged beyond said shearing organization for engaging the presented edge of a sheet and formed to register said sheet accurately both transversely and lengthwise of the sheet, said movable device moving in timed relation with said shearing organization to accomplish the sheet registration.

7. In a shear press for forming strips with scroll edges and from which disks may be cut as for the forming of can ends and the like, the combination of cooperating dies for shearing the sheet of metal transversely and adapted to provide the scroll edges, feeding mechanism for advancing the sheet into position for operation of the dies and a device engaging a recess of a scroll edge left in the sheet by an operation of said die for registering the sheet with respect to the dies and transversely of the travel of the sheet.

8. In a shear press for forming strips with scroll edges and from which disks may be cut as for the forming of can ends and the like, the combination of cooperating dies for shearing the sheet of metal transversely and adapted to provide the scroll edges, feeding mechanism for advancing the sheet into position for operation of the dies and a device shaped to conform to the scroll cut by said die and adapted to engage a sheet edge to register the same.

9. In a shear press for forming strips with

scroll edges and from which disks may be cut as for the forming of can ends and the like, the combination of cooperating dies for shearing the sheet of metal transversely and adapted to provide the scroll edges, feeding mechanism for advancing the sheet into position for operation of the dies, and a device shaped to engage the scroll edge of the sheet produced by a cut of the die, said device being movable toward and from the presented sheet edge to register the sheet both transversely of and in the direction of its travel as it is moved into cutting position.

10. In a shear press for cutting a sheet of metal into transverse strips having edges of predetermined configuration, the combination of a shearing organization, means feeding the sheet progressively into shearing position and devices arranged on opposite sides of said shearing organization for registering said sheet laterally of its direction of travel in accurate registration with said dies, the device at one side of the sheet being connected with the press mechanism and thereby pressing the sheet against the opposite device.

11. In a shear press for cutting a sheet of metal into transverse strips having edges of predetermined configuration, the combination of a shearing organization, means feeding the sheet progressively into shearing position and devices arranged on opposite sides of said shearing organization for registering said sheet laterally of its direction of travel in accurate registration with said dies, some of said devices being power actuated and moved in timed relation to said shearing organization.

12. In a shear press adapted to cut a sheet of metal into transverse strips, the combination of a bed across which sheets of metal are adapted to be successively fed, a shearing organization associated with said bed, means feeding the sheet along said bed into said shearing organization, a guiding device arranged upon said bed and adjacent the end remote from said shearing organization for positioning said sheet transversely with respect to its path of travel, a movable gauging device arranged between said first mentioned device and said shearing organization and connected with the press mechanism and pressed thereby against the side edge of the sheet, for initially gauging said sheet across its path of travel, and gauging devices arranged adjacent said shearing organization for finally gauging said sheet to position it into predetermined relation with said shearing organization.

13. In a shear press for cutting a sheet of metal into transverse strips having scroll edges, the combination of a shearing organization, means for feeding the sheet progressively into shearing position, devices arranged on opposite sides of said shearing organization and cooperating with each other

- to register said sheet relative to said shearing organization along one of its scroll edges, the device at one side of the sheet being connected with the press mechanism and thereby pressing the sheet against the opposite device, devices for holding said sheet in registered position during the cutting operation, and means for moving some of the last mentioned devices to discharge a strip from cutting position after the same has been severed from the sheet.
14. In a shear press for cutting a sheet of metal into transverse strips having scroll edges, the combination of a shearing organization, means for feeding the sheet progressively into shearing position, devices for registering said sheet relative to the shearing organization, including a centering gauge engaging the front scrolled edge of the sheet, members associated with said devices for holding the sheet in registered position for the cutting operation of the shearing organization, and means for actuating said holding members to permit discharge of a strip cut from the sheet.
15. In a shear press for cutting a sheet of metal into transverse strips having scroll edges, the combination of a shearing organization, means for feeding the sheet progressively into shearing position, devices for registering said sheet relative to the shearing organization, members associated with said devices for holding the sheet in registered position for the cutting operation of the shearing organization, and means for actuating said holding members to release a strip cut from said sheet, and means for discharging said strip from cutting position.

MATTHEW LEE HEALD.
